W. W. GUY

FIREPLACE DAMPER

Filed May 1, 1926

UNITED STATES PATENT OFFICE.

WALTER W. GUY, OF OAK PARK, ILLINOIS, ASSIGNOR TO COLONIAL FIREPLACE COMPANY, OF CHICAGO, ILLINOIS, A CORPORATION OF ILLINOIS.

FIREPLACE DAMPER.

Application filed May 1, 1926. Serial No. 106,085.

My invention relates to fireplaces, and more specifically to an improved means for controlling the opening in the fireplace throat.

Among the primary objects and advantages of the invention may be enumerated the production of a convenient and inconspicuous means for controlling the throat opening, preferably without penetrating any of the brickwork. Stated more specifically, this involves adequate leverage and good accessibility when the device is being operated, combined with means for keeping the operating handle, or lever, out of sight and out of the way when not in use.

Another object is adjustability to accommodate fireplaces of different dimensions.

Further objects and advantages of the invention will become apparent as the description proceeds.

In the accompanying drawings:

Figure 1 is a transverse section through a fireplace equipped with a damper according to the invention;

Figure 2 is a partial front elevation of the parts shown in Figure 1 with most of the brickwork removed; and

Figure 3 is a diagrammatic plan as in section on line 3—3 of Figure 1.

In the embodiment of the invention selected for illustration, the fireplace comprises the usual back wall 10 and arch wall 12, preferably thickened at 14, to leave an exit at 16 for the products of combustion, which exit is commonly referred to as the throat. The dome 18 preferably comprises a front wall 20 and a rearwardly extending portion 22 resting on the angle of the back wall 10 and cut away to provide the throat opening. The lower edge of the damper 24 rocks in suitable notches formed on the portion 22 of the dome. As the foregoing structure is old and well known in the art, and described in detail in Patent No. 1,105,651, issued to me August 4, 1914, detailed disclosure of these portions is deemed unnecessary.

In the design illustrated the front portion of the arch wall extends down a considerable distance below the enlargement 14 and its lower rear edge is protected and reinforced by an angle 26.

On the wall 20 I mount a depending bracket 28 having a horizontal offset 30 at its lower end. In the horizontal offset I

pivot a vertical shaft 32 having a D-shaped section, as clearly indicated in Figure 3. The arms 31 of the offset 30 may be connected in the usual way by an adjusting screw 34 for controlling the friction, as described hereinafter.

Above the offset 30 I mount a gear 36 fastened on the shaft against both rotation and sliding movement as by a set screw 38, and having bevel teeth 40. The teeth 40 mesh with cooperating teeth on the hub 42 of the crank arm 44. This crank arm is journaled on a horizontal pivot formed by a bolt having a shank 46 extending through the vertical portion of the bracket 28, and a head 48 rotatably receiving the end of the shaft 32 above the gear 36. Thus, the bolt interconnects the pin 46 and the upper end of the shaft 32, so that they brace and strengthen each other.

The upper end of the crank arm 44 is connected to a lug 50 on the damper member 24 by means of a pair of links 52, with pivot pins, or rivets, 53 at their ends.

The butt section 54 of the operating arm 80 is rigidly fastened to the lower end of the shaft 32 and is provided with a U-shaped depression 56 for receiving the telescoping handle section 58. A pair of screws 60 sliding in a slot 62 in the bottom of the operating arm constitute suitable means for maintaining the telescopic engagement.

At the outer end of the handle member 58 I position a downwardly extending knob 64 to be grasped by the hand of the operator. Above the knob 64, I prefer to provide a small indicator plate 66 on which are inscribed "Shut" and "Open" with appropriate arrows to guide the operator in manipulating the device.

When the device is not in use, the knob 64 is preferably pushed back under the edge of the arch wall, as indicated in Figure 1. To adjust the damper, the handle section 58 can be slid out to project beyond the arch wall, and the increased leverage resulting makes the subsequent turning movement of the arm easy and convenient. After the adjustment is completed, the arm can be slid back out of sight.

The friction of the parts, with the set screw 34 loose, is not quite sufficient to hold the parts in adjusted position, but when such friction is supplemented by a slight tightening of the set screw, it is found that the de-

vice can be made self-locking in any position, and that it will remain so over a long period of use.

The vertical adjustability of the rod 32 in the bracket, and of the butt section 54 on the rod, make it possible to sell a stock mechanism that will fit almost any fireplace. Thus, while three courses of brick below the throat are usual, many are built with two, or one. In such a fireplace it is a simple matter to slide the rod up about the height of one course and the butt section up on the rod for further adjustment. Similarly, in some more expensive installations, a stone slab may be used instead of the brick arch wall. The telescopic mounting of the handle section 58 will take care of all ordinary variations in arch wall thickness.

The bracket 28 may be installed on the plate 20 after the fixed parts of the structure have been built into place. Removal of the bracket and one of the pivots 53 connecting up the links 22, will enable a workman to take out and replace the entire operating mechanism and the damper member, which latter can be lifted up into the clear space above it and turned endwise to remove it.

Without further elaboration, the foregoing will so fully explain the gist of my invention, that others may, by applying current knowledge, readily adapt the same for use under various conditions of service. The set screw 38 permits vertical adjustment of the operating arm 54 to fit arch walls of different heights, and it will be obvious that the advantages of the structure disclosed would still be present in case it were preferred to have the handle section stick 40 through a narrow slot in the arch wall above the lower edge of the same. Without eliminating certain features which may properly be said to constitute the essential items of novelty involved, which items are intended 45 to be defined and secured to me by the fol-

lowing claims; these and many other modifications may readily be made by those skilled in the art.

I claim:

1. The combination with a fireplace having a throat, of a damper comprising a pivoted damper member in said throat, a bracket in front of the throat, a crank arm journaled on said bracket, a link connecting said crank arm and damper member, a downwardly extending vertical shaft journaled on said bracket, an operating arm on the lower end of said shaft, said arm comprising a butt section and a handle section telescoping on said butt section, and a gear transmission connecting said shaft and said crank arm. 50

2. The combination with a fireplace having a throat, of damper means comprising a damper member in said throat, a bracket in front of the throat, a crank arm journaled on said bracket, a link connecting said crank arm and damper member, a downwardly extending vertical shaft journaled on said bracket, an operating arm on the lower end of said shaft, said arm comprising a butt section and a handle section telescoping on said butt section, and a gear transmission connecting said shaft and said crank arm. 65

3. The combination with a fireplace having a throat, of damper means comprising a movable damper member, a bracket in front of said member, a crank arm journaled on said bracket, a link connecting said crank arm and damper member, a shaft journaled on said bracket, an operating arm on said shaft, said arm comprising a butt section and a handle section telescoping on said butt section, and an operative connection between said shaft and said crank arm. 70

75

In witness whereof, I hereunto subscribe my name this 24th day of April, 1926.

WALTER W. GUY.
